UNITED STATES PATENT OFFICE.

BERNHARD GRUNWALD, OF OMAHA, NEBRASKA.

OIL BURNER.

Application filed March 8, 1925. Serial No. 12,853.

My invention relates to means for burning relatively heavy liquid fuels, such as kerosene, distillate and fuel-oil, and adapted to be used in furnaces originally constructed for burning coal or other solid fuel, whereby to convert the same into oil-burning furnaces. It is the object of my invention to provide a burner which may be readily applied to furnaces of the class above mentioned, and with which heavy liquid fuels may be efficiently burned without the production of fumes or smoke. A further object of my invention is to provide a burner of this class in which the generator or oil-vaporizing means are readily accessible so that any deposit of carbon or other solids may be conveniently removed from time to time as the accumulation thereof may require. A further object of my invention is to provide in a burner of this class a generator or oil-vaporizer positioned externally of the combustion chamber and heated therefrom by conduction through relatively massive metallic members extended between the generator and the combustion area. A further object of my invention is to provide in a burner of this class means by which the supply of air and fuel may be regulated simultaneously so as to automatically maintain substantially constant proportions thereof, and in which the ratio of openings of the main air-passage and fuel-valve may be varied to compensate differences in the draft of furnaces to which the burner may be applied.

In the accompanying drawings Fig. 1 is a longitudinal vertical section on line 1—1 of Fig. 2 of a burner embodying my invention, Fig. 2 is a front view of the same, Fig. 3 is a transverse section on the line 3—3 of Fig. 1, Fig. 4 is a detail section on the line 4—4 of Fig. 2, and Fig. 5 is a side view of the burner, disposed in operative relation to a furnace of which portions are broken away to expose the inclosed portion of the burner.

In carrying out my invention according to the illustrated embodiment thereof, I provide a rectangular box-like case or housing 5 which may be of cast metal with rather thick walls, the bottom of the box being flat and extending at a uniform level, the sides being in uniform vertical planes, and the top having two shoulders or offsets therein, the first shoulder 6 being near the front end, and the second shoulder 7 being intermediate the first shoulder and the rear end. The

housing 5 is open at the front end and at the upper side between the rear end and the shoulder 7. In applying the burner to a furnace A of a type such as illustrated in Fig. 60 5, the grate used for burning solid fuel is removed from the furnace, and the upper door B, through which the coal or the like is ordinarily supplied, is tightly closed and not used. The lower or ash-pit door C is 65 provided with an opening just large enough to receive the portion of the housing 5 behind the shoulder 6, and the housing is mounted upon said door so that the portion behind said shoulder 6 extends into the furnace, while the front portion of the housing projects from the door at a moderate elevation from the floor or base on which the furnace rests.

At the front end of the housing 5, and covering approximately the lower half of the opening, is a door 8 which is hinged at its lower portion, so as to be openable by swinging forwardly and downwardly. Latch-hooks 9, pivoted at the sides of the housing, 70 80 are adapted to engage pins 10 extending laterally from the edges of the door, for holding the door normally in closed position. The inner sides of the housing adjoining the door 8 are rabbeted to form guideways for 85 the edges of the air-check plate 11, which fits against the inner side of the door 8 as shown in Fig. 1, and is slidable vertically from the lower or fully open position shown in said figure to a raised position at which the upper edge of the plate engages the top of the housing and the plate thereby closes the front opening thereof above the door 8.

At the center of the plate 11 is a vertical arm 12 which extends up through a notch in the front edge of the housing, said arm at its upper end having a fixed rearwardly extending pin 13 which is engaged in a slot at the end of the control-lever 14. At the center of the door 8 an arm 15 is extended upwardly 90 95 therefrom, said arm having at the upper end a head 17 adapted to fit over the notch in the housing through which the arm 12 passes, whereby to form a guide for said arm when the door is in closed position. When the door 8 is opened the plate 11 remains suspended from the control-lever 14, and the plate may be entirely removed from the assembly by merely lifting and moving the same forwardly, to disengage it from its 100 105 guideways and to withdraw the pin 13 from the slot in the control-lever. By the open-

110

ing of the door 8 and removal of the plate 11, the entire front end of the housing is opened so that the interior thereof is made freely accessible for the inspection, removal, 5 cleaning and replacing of the generator or vaporizing devices contained therein.

The portion of the housing in front of the shoulder 6 incloses the generator-chamber, and in the upper portion of said chamber is removably disposed the generator or oil-pan 18 which is a shallow rectangular receptacle extending transversely of the housing, and having thick walls, its outer sides being horizontally ribbed and spaced 10 from the sides of the housing, as shown. Said pan 18 rests upon the upper edges of a pair of thick vertical plates 19 which are disposed removably upon the bottom of the housing, said plates having at their lower 15 portions the laterally extending foot-lugs 20 adapted to engage the adjacent sides of the housing for maintaining a suitable spacing between the plates and said sides. Horizontally ribbed lugs 21 extend down from the 20 pan 18 into the space between the plates 19, and the position of the pan longitudinally of said plates is gaged by shoulders formed on the upper edges of the plates at the rear side of the pan. The rear portions of the plates 25 19 extend back into the retort or mixing-chamber which is inclosed by the portions of the housing intermediate the shoulders 6 and 7, and the longitudinal position of the plates is fixed by the placing thereof between the 30 transverse ribs 22 and 23 which are formed integrally with the housing and extend from side to side across the bottom-plate thereof. Said ribs 22 and 23 also serve to form at the bottom of the housing a pan or receptacle for 35 receiving any of the liquid which may overflow from the generator 18 and reach the bottom of the housing without being vaporized. At one side of the housing, and connecting with the space intermediate the ribs 22 and 40 23, is a drain-pipe 24 through which any excess of the fuel may escape from the receptacle. On the upper side of the housing, above the central portion of the pan 18, a cup 25 is formed integrally with the top-plate, and from the bottom of said cup a 45 hole 28 is extended through the top-plate, said hole terminating at an annular lip 26 extending slightly below the lower or inner surface of the top-plate. The feed-pipe 27, 50 through which the liquid fuel is delivered, is arranged to terminate above the cup 25 and is positioned centrally thereof, so that normally the liquid will drop through the hole 28 and into the pan 18 without touching the cup or any portion of the housing. If, however, the falling liquid should be 55 slightly diverted laterally, so as not to pass directly through the hole, it will be caught by the cup and flow down the inside thereof 60 through the hole, finally dripping off the lip 65

26, which will prevent the liquid clinging to the inner surface of the housing and flowing along the same so as not to be delivered into the pan 18.

The feed-pipe 27 is supported by any suitable means (not illustrated), and at a point adjacent to one side of the housing the pipe is provided with a safety shut-off valve 29. Said valve may be of the well-known type commonly used in connection with oil-burning devices, and in which the closing of the valve to shut off the supply of fuel is effected automatically by a slight increase of weight upon a trigger or trip-lever. Such a trigger or trip-lever 30 is indicated in the 70 drawing, and a cup or small bucket 31 is suspended therefrom, the same being positioned to receive liquid from the drain-pipe 24, whereby a dripping of oil from said drain-pipe, due to overflow of unburned fuel, 75 will operate the trip-lever to close the valve and thus automatically stop the supply of fuel to the burner. The feed-pipe 27 is also provided with a fuel-regulating valve 32 which, in the structure illustrated, is arranged for manual control. The valve-stem 33 has a hand-wheel 34 fixedly mounted thereon, and to said stem is also affixed an indicator or pointer 35 and an arm or crank 36. The pointer is movable adjacent to a 80 graduated quadrant 37 which is secured to the valve-casing, and the crank-arm 36 is movable adjacent to a quadrant 38 having a series of holes 39 for receiving a pin or screw 40 by which the arm may be connected 85 with the quadrant in fixed positions of adjustment. One end of the control-lever 14 is pivotally connected with the outer end of the crank-arm 36, and the valve is so proportioned that in the adjustments thereof 90 from a maximum to a minimum fuel-supply the arm and the attached end of the lever are moved between the positions shown, respectively, by full and dotted lines in Fig. 2. The intermediate portion of the control-lever 14 is slotted as shown, and rests slidably and pivotally upon an adjustably movable fulcrum which is supported upon a standard 41 extended up from the burner-housing 5. At the upper end of said standard 95 is a slotted head 42, the direction of the slot in said head being such that it is parallel with the slot in the lever when the latter is at the position corresponding with the minimum opening of the fuel-valve, as indicated 100 by the dotted lines in Fig. 2. The adjustably movable fulcrum is formed by a bolt 43 which fits slidably in the slot in the head 42, a sleeve or collar 44 being disposed about the portion of the bolt which passes through the slot in the lever 14, and the axial length of the said sleeve being slightly greater than the thickness of the lever. Washers 45 are disposed upon the bolt between the head 105 thereof and the end of the sleeve 44, and be- 110

tween the head 42 of the standard and the nut 46 which is screwed upon the threaded end of the bolt. Referring to Fig. 4 it will be seen that by tightening of the nut the sleeve 44, which forms the actual fulcrum of the lever, may be clamped to the head 42 in any position of adjustment longitudinally of the slot in said head, and the lever-fulcrum thus varied between said limits of adjustment. It will be obvious that as the fulcrum of the lever is varied the ratio of movement between the fuel-valve and air-check plate will be varied accordingly, shortening of the valve-arm of the lever, for example, resulting in a greater movement of the check-plate during the same adjusting movement of the valve. It will also be seen that, as the slots in the control-lever and the head 42 are coincident or in longitudinal register when the check-plate is in closed position and the fuel-valve at minimum opening, adjustments of the fulcrum will not change the relation of the valve and plate at said minimum-opening position, but the variation of the lever-ratio will result in increasing or decreasing, as the case may be, the area of the air-passage controlled by the plate 11, when the fuel-valve is at any position other than that of minimum opening. Holes 47 in the upper front portion of the housing are adapted to admit to the generator-chamber sufficient air for maintaining a pilot-flame when the fuel-supply is reduced to the minimum and the main air-supply shut off by the check-plate 11.

In the normal operation of the described mechanism, after the same has become thoroughly heated and when there is an adequate supply of fuel and air, the mixing of the fuel-vapor with a proper proportion of air for combustion thereof occurs during the passage of the gaseous materials rearwardly from the generator-chamber through the retort or mixing chamber, and the combustion of the fuel commences near the rearward end of said chamber, continuing out into the open-topped fire-pan or rearward portion of the housing. When properly regulated, a clean white flame rises from the fire-pan into the combustion-chamber of the furnace, substantially as indicated in Fig. 5, the flame being directed so as not to strike the furnace-walls and deposit soot thereon. The heat from the combustion zone is conducted by the thick walls of the burner-housing to the outer end thereof about the generator-chamber, and the plates 19 serve to conduct heat directly to the generator or oil-pan 18 for keeping the same at the required temperature for vaporizing the liquid fuel. The air and oil-vapors while passing rearwardly through the mixing-chamber or retort are heated by radiation from the plates 19 and the walls of the housing, the radiation being increased by reason of the longitudinal ribs or corrugations 48 on the vertical inner sides of the housing. When the supply of fuel is reduced by partial closing of the fuel-valve, the air-supply is correspondingly reduced by the raising of the air-check plate 11, the rate of flow of the air and oil-vapor through the housing is thus reduced, and by reason of the reduced rate of flow the combustion commences at a point nearer to the front of the housing. When the supply of the liquid fuel is reduced to a minimum, and the air-supply accordingly limited to that which enters the housing through the holes 47 and 28, the draft through the housing becomes so reduced that combustion of the limited supply of fuel takes place directly at the pan 18, which is thus kept heated sufficiently to continue the vaporization of the liquid, and thereby to maintain a pilot-flame about the marginal portions of the pan. When the fuel-supply is increased, after operating for a time at the minimum rate, there may be at first a slight overflowing of the pan 18, whereby the oil will pass down over the ribbed outer surfaces of the pan and its depending lugs 21 in a thin sheet or film, the oil being thus subject to rapid heating and vaporization, so that a large flame is quickly produced. At the same time the greater air-draft resulting from the opening of the air-check 11 sweeps the increasing volume of oil vapors rearwardly through the housing, so that the point at which combustion commences will be nearer to the rear end of the housing, and the heating of the generator again effected by conduction through the plates 19 and the housing-walls. In starting the operation of the burner, the pan 18 may be initially heated by placing therein a small quantity of volatile liquid fuel and igniting the same, or if the regular fuel is not too heavy a small charge thereof may be run into the pan, ignited, and burned for a sufficient time to heat the same to generating temperature before starting the continuous supply of fuel thereto. Starting of the burner may also be effected by entirely removing the pan 18 from the housing, heating the pan by any desired external means, then replacing the same in the burner, starting the fuel supply, and igniting the vapors produced when the liquid fuel begins to flow into the heated pan. The removal of the pan is readily effected after opening the door 8 and lifting out the plate 11, as hereinbefore explained. Substantially the same procedure may be employed when it is desired to remove from the pan any accumulation of solids therein such as result from the use of heavy fuels which have non-volatile residues. If the cleaning of the pan is effected with reasonable rapidity, it may be taken out of the housing, cleaned, and replaced before it will have become cooled below the generating temperature, so that the

4
operation of the burner may be immediately resumed, without re-generating.

It will be particularly noted that the automatic and simultaneous variation of the fuel and air supply to the burner, effected by the control-lever 14, insures a correct and economical combustion of the fuel at all rates of operation of the burner, by so proportioning the supply of fuel and air that for any rate of fuel-feed there will be neither a deficiency of air for complete combustion, nor an excess of air tending to reduce the temperature of the combustion products. By adjustments of the movable fulcrum of the control-lever, the operation of said lever may be so regulated as to readily compensate for differences of draft in various furnaces to which the burner may be applied, and after the draft-adjustment has been made, the fuel and air will be properly proportioned for all rates of fuel-feed.

Now, having described my invention, what I claim and desire to secure by Letters Patent is:

25. 1. An oil burner, comprising a housing having an open-topped rear portion forming a fire-pan and extending into the combustion chamber of a furnace, the front portion of said housing inclosing a generator-chamber and extending externally of the furnace, and the intermediate portion of the housing inclosing a mixing-chamber connecting the generator-chamber and the fire-pan, heat-conductive members extending longitudinally of the mixing-chamber and into the generator-chamber, a generator supported upon said heat-conductive members in spaced relation to the walls of said chamber, means for supplying liquid fuel to said generator, and means for controlling admission of air to said chamber.

2. An oil burner, comprising a thick-walled heat-conductive housing having a generator-chamber at the front portion thereof and said portion arranged externally of a furnace, said housing having an open rear portion extending into the heating chamber of the furnace, and the intermediate portion of the housing inclosing a mixing-chamber communicating with the open rear portion and with the generator-chamber, heat-conductive plates removably disposed within and extending longitudinally of the mixing-chamber and into the generator-chamber, a generator comprising a shallow receptacle for liquid fuel support-

ed removably upon said plates within and spaced from the walls of said generator-chamber, a door partially closing the end of the housing adjoining said chamber, and a draft-controlling plate normally guided by said door and movable to positions for restricting the opening past the door, said plate being removable from the housing when said door is opened, whereby to afford free access through said opening to the generator-chamber.

3. An oil burner, comprising a horizontally disposed housing having an open rear portion extending into the heating chamber of a furnace, the front portion of said housing inclosing a generator-chamber and extending externally of the furnace, a shallow thick-walled oil-pan having horizontally ribbed outer surfaces and disposed in said generator-chamber in spaced relation to the walls thereof, heat-conductive members supporting said oil-pan and extending therefrom through the housing into proximity to the open rear portion thereof, a feed-pipe for liquid fuel, said pipe terminating outside the housing above said oil-pan and arranged to deliver the fuel to said pan through an opening in the top of the housing, a valve for controlling the flow of liquid through said pipe, draft-controlling means movable to regulate admission of air to the generator-chamber, and means connecting said fuel-valve and draft-controlling means to coordinate adjustments thereof.

4. In an oil burner, a housing inclosing a generator chamber in the front portion thereof and having a passage of reduced sectional area extending rearwardly from said chamber and communicating with an open fire-pan, said rear portion of the housing extending into the heating chamber of a furnace and the front portion projecting externally of the furnace, an oil-pan disposed in said generator-chamber, heat-conductive members extending from said oil-pan through the passage toward the rear portion of the housing, the housing having an opening therein above the oil-pan, a feed-pipe for liquid fuel, said pipe terminating above said opening in the housing, a cup formed on the top of the housing about said opening, and an annular lip formed about said opening at the inner end thereof for the purpose described.

BERNHARD GRUNWALD.
